BOTTLE FILLING VALVE

James Kantor, Chicago, Ill., assignor to The Liquid Carbonic Corporation, Chicago, Ill., a corporation of Delaware

Application October 28, 1933, Serial No. 695,594

5 Claims. (Cl. 226—122)

My invention relates to improvements in filling valves for bottle filling machines and has for one of its objects that of providing a dripless valve of this type.

5 Another object of the invention is to provide means whereby liquid is prevented from backing up into the gas line in event, for any reason, the apparatus is stopped during a filling operation.

10 My invention is particularly applicable to the type of valve illustrated in my U. S. Letters Patent No. 1,900,447 granted March 7, 1933 and reference may be had to this patent for details of construction of the filler valve not specifically referred to in the present application.

15 For the purpose of disclosing my invention I have illustrated an embodiment thereof in the accompanying drawing in which

Fig. 1 is a longitudinal sectional view of a valve embodying my invention and

20 Fig. 2 is a detail sectional view of a filling machine showing the position of the valve with respect to that machine.

As is usual in this type of machine there is provided a filling tank 1 adapted to contain carbonated water or other liquid to be supplied to the bottle to be filled. This tank is provided with a series of filling valves 2 adapted to be engaged by the bottles to be filled and control the flow of liquid to the bottle from the tank 1.

25 In the specific form of valve illustrated a base casting 3 is provided having a water inlet port 4 controlled by a valve 5 and a counter pressure gas inlet port 6 controlled by the valve 7. The stems 8 and 9 of these valves project below the casting and it will be noted that the stem 9 is longer than the stem 8. The water inlet port 4 is connected by a suitable pipe 10 with the filling tank 1 and the counter pressure gas inlet port 6 is connected by the pipe 11 with the top of the 30 tank 1. To this end there is provided a pipe 12 in the tank 1 which extends above the water level in the tank and communicates with the pipe 11.

35 In addition to the two above-mentioned ports there is also provided a snifter port 13 adapted to communicate with the atmosphere. The water inlet port 4 communicates with the water tube 14 extending downwardly from said base 3 and the gas port 6 communicates with a counter pressure tube 15 likewise extending downwardly from said casting and telescoping the tube 14. The snifter port 13 communicates with a snifter tube 16 likewise extending downwardly from the base 3 and telescoping the other two tubes, this tube 16 being considerably shorter than the remaining 40 tubes.

Surrounding the tubes is a valve-operating member comprising a casing 17 biased in its downward position by a coiled spring 18 interposed between a shoulder 19 within the casing 17 and the bottom of the base 3. This casing 17 reciprocates on a tubular extension 20 from the base 3 and is restrained against movement in one direction by an annular shoulder 21 which engages beneath the collar 22. The lower end of this casing 17 is provided with a bottle-engaging 10 throat 23.

The lower end of the water tube 14 is closed by a valve 24 seating on the bottom edge of the tube and provided with a socket for the reception of the tube, the walls of which socket are provided 15 with openings 25 whereby when the valve is moved to open the lower end of the water tube the water discharge will take place through the openings 25 and be discharged against the side walls of the bottle rather than downwardly. This valve 24 is controlled by a valve-operating rod 26 which extends upwardly through the water tube 14 and is provided at its upper end with a threaded nut 27 which is screwed into a piston member 28 having a preferably leather cup 29 on the top thereof. 25 This piston operates in a cylindrical tube 30 extending into an opening in the base 3 and terminating in the port 4. This piston 28 in turn is connected with a second piston 31, also operating in the tube 30 and likewise provided with a cup 30 32. The two pistons are connected to a stem 33 extending beyond the tube by means of a rivet 34 and this stem at its upper end has an annular shoulder 35, in the form of a nut threaded thereon at its upper end. Between this nut and a part 35 of the base 3 is arranged a coiled spring 36, which, through the connections heretofore described, biases the valve 24 in a closed position. The valve is adapted to be opened by a suitable operating lever 37 bearing upon the nut 35 and operated in its proper sequence by the operating member 17.

The pipe 11 communicates with the port 6 through the medium of suitable openings 38, 39 and 40 in the casing and in the opening 39 there is provided a valve seat 41 on which is adapted to seat a float valve 42, which may be of any suitable light material as cork or the like and biased in an open position by gravity. This valve is preferably hung upon a stem 43, somewhat in 50 the form of a cotter pin and having its ends 44 turned over a cross bar 45. In normal operation of the apparatus this valve, due to gravity, will remain in its open position.

In the operation of the device when the bottle 55

engages the throat 23 this throat, with the bottle, is forced upwardly, thereby projecting the water tube 14, the gas or counter pressure tube 15 and the snifter tube 16 into the bottle. The continued 5 upward movement of the casing 17 causes the same to engage the stem 9 of the valve 7, opening this valve and admitting the counter pressure gas from the top of the tank 1 through the pipes 12 and 11 until the air in the bottle has been 10 expelled and the bottle is filled with the carbonic acid gas at a pressure equal to that within the tank 1. As the casing continues to move upwardly it then engages the stem 8 opening the valve 5, the valve 7 still being open, and water 15 from the tank 1 is admitted through the pipe 10 into the filling tube 14. At the same time that the valve 5 is opened the lever 37 is operated to 20 depress the rod 26, thereby opening the valve 24 and water flows from the tank into the bottle, forcing carbonic acid gas back up through the counter pressure tube into the tank. By the time the bottle has been filled with water sufficient 25 counter pressure has been developed to stop the flow of water and at this time, likewise, the bottle begins to move downwardly again. This downward movement of the bottle first shuts the valve 5 shutting off the flow of water and at the same 30 time permits the closure of the valve 24 under the influence of the spring 36 so that the bottom of the water tube is closed and the water remaining in the tube after the closure of the valve 5 will not flow into the bottle. The counter pressure 35 valve 7 next closes, shutting off the passage of carbonic acid gas from the top of the tank and, at about the same time, the snifter valve is opened to permit the escape of any excess gas from the top of the bottle to the atmosphere.

The pistons 28 and 31 act to seal the top of the water tube 14 against the escape of water 40 through the top thereof and take the place of packing glands. It will be noted that some means must be provided for the operation of the stem or rod 26 from the exterior of the tube and to provide an operating means and at the same time 45 prevent the leakage or escape of water I provide the pistons 29 and 31. Heretofore it has been the custom to provide a packing gland at this point through which the stem 26 extends. An objection to such an arrangement is that there is always an uncertainty as to whether the operator 50 will get the packing gland adjusted correctly. In his eagerness to prevent leakage he is very apt to get the packing gland set too tight and as a result frictionally bind the stem 26 so that the spring 36 cannot properly operate to close the valve 24. This results in a leaking of the valve. Furthermore due to the fact that there is a certain amount of carbonated water trapped in the water tube 14 when the valve 24 is closed the 55 carbon dioxide gas liberated from this water is apt to create a pressure in the tube thereby tending to open the valve and permit dripping. This is particularly so when highly carbonated water is being used. The pistons 29 and 31 seal the top of the tube against the escape of the water with a minimum friction engagement between the parts so that the stem will be free to operate as possible. This stem is raised through the medium of the coiled spring 36 and in order to have the 60 parts operate promptly and efficiently the binding action on the stem, where it passes to the exterior of the apparatus, should be reduced to a minimum. The area of the pistons is equal to the effective pressure area of the valve 24, when 65 closed. The carbonated water, due to the libera-

tion of a small proportion of the carbonic acid gas in the water tube 14, with the valve 5 closed and with the valve 24 closed, develops a certain amount of pressure against the valve 24, as well as the weight of the water. Due to the fact that 5 the effective pressure area of the piston 29 is equal to the effective pressure area of the valve 24 when closed, this opening pressure of the gas is counter balanced and the only opening pressure which has to be contended with is the weight 10 of the water contained in the water tube. Therefore, the spring 36 may be very nicely adjusted to take care of the weight of the water and at the same time parts are quickly responsive for 15 opening and closing. I have found that by making the effective area of the piston 29 equal to the effective area of the valve 24 very advantageous results may be obtained. However in some instances the area of the piston 29 may be greater than the area of the valve 24 and the parts operate satisfactorily. It will be noted that due to the fact that the effective pressure area of the piston 29 is equal to or greater than the area of the valve 24, an extremely light spring 36 may be used as about all the work this spring has to do is 20 to overcome the friction of the moving parts as the pressure is compensated for by the piston.

Some times during the operation of the filling machine the machine is stopped with the valve 5 open and with the valve 7 open. Under these 30 circumstances, with the tendency of the water to seek its level, the water will back up in the counter pressure tube 15, through the ports 6, the openings 40, 39, and 38 and through the pipes 11 and 12 until the water in the pipe 12 reaches the 35 level of the water in the tank 1. This water remains in the counter-pressure tube and ports even after the bottles which have been filled have been discharged from the filling machine. As soon now, as the machine again starts the water 40 which has backed up in the counter-pressure tube and ports will be forced out of the tube and the pipes 11 and 12 under the pressure of the gas in the top of the tank into the next succeeding bottle to engage the valve. This delivers this water into 45 the bottles with such a rush as to cause foaming, which foam remains on top of the syrup which has previously been discharged into the bottle. As soon as the carbonated water flowing through the valve from the tank contacts with this foam a 50 violent liberation of the carbonic gas from the carbonated water takes place with a result that when bottles are discharged from the filling machine approximately one-sixth of the contents boils out. Furthermore, the contents of these 55 bottles will be found to be under standard as to the degree of carbonation because of the fact of the liberation of so much of the carbonic acid gas. By the provision of the float valve 42 the backing up of the water in the counter-pressure 60 tube and in the opening 40 will float this valve 42 closed, thereby preventing further backing up of the water into the pipes 11 and 12, thus preventing the delivery of a large quantity of water into the bottle from the pipes 11 and 12 when the machine is again started. Of course, that water 65 in the counter-pressure tube and in the opening 40 will flow back into the bottle, but this is comparatively negligible.

I claim as my invention:

1. In a bottle filling valve, the combination with a valve casing, of a filling tube supported by and extending downwardly from said casing and open at its lower end, a valve controlled inlet port in said casing communicating with said 75

5 tube, a downwardly opening valve at the lower end of said tube for controlling the passage of liquid from said tube, a stem extending through said tube for operating said valve and projecting through the top of said casing for engagement with operating means, said casing having an opening in the top thereof through which said stem projects and communicating with said tube, and a piston connected to said stem and 10 operating in said opening to seal said opening against the escape of liquid through the top of the casing.

15 2. In a bottle filling valve, the combination with a valve casing, a filling tube supported by and extending downwardly from said casing and open at its lower end, a valve controlled inlet port in said casing communicating with the top of said tube, a downwardly opening valve at the lower end of said tube controlling the discharge 20 of liquid therefrom, a stem extending through said tube for controlling said valve and projecting through an opening in the top of said casing and above the top thereof for engagement with operating means, and a packing surrounding 25 said stem within said opening and connected to and movable with said stem.

3. In a bottle filling valve, the combination with a valve casing, of a filling tube supported by said casing and extending downwardly from 30 said casing and open at its lower end, a valve controlled inlet port in said casing communicating with the top of said tube, a downwardly opening valve at the lower end of said tube for controlling the discharge of liquid from said 35 tube, a stem extending through said tube and projecting above the top of said casing for engagement with operating means with said valve, a tubular extension communicating with said

tube projecting through said casing and surrounding said stem, a piston in said tubular extension connected with said stem, the effective area of said piston being equivalent to the effective area of the valve at the lower end of the 5 tube, and means biasing said valve to closed position.

4. In a bottle filling valve, the combination with a valve casing, of a filling tube supported by said casing and extending downwardly from 10 said casing, a valve controlled inlet port in said casing communicating with the top of said tube, a valve at the lower end of said tube for controlling the discharge of liquid from said tube, a stem 15 extending through said tube and projecting through an opening in the top of said casing, a tube extending above said opening, a threaded stud secured to the upper end of said stem, a piston member comprising an internally threaded stud for receiving the threaded stud on said 20 stem, a pair of pistons, piston packing covering said pistons, a clamping member, and a stem for clamping said hollow threaded member and pistons and piston packing together, said structure 25 operating within said tubular extension.

5. In a bottle filling valve, the combination with a valve casing, of a filling tube supported by said casing and extending downwardly from said casing, a valve controlled inlet port in said casing communicating with the top of said tube, 30 a valve at the lower end of said tube for controlling the discharge of liquid from said tube, a stem extending through said tube and through an opening in the top of said casing, a threaded stud secured on the upper end of said stem, and 35 a piston internally screw-threaded for engagement with said stud operating in said opening.

JAMES KANTOR.
